DRESS-SUPPORTING FORM

Leona M. Lennemann, 2115 Pennsylvania Ave. NW,
Washington, D.C.

Filed Sept. 29, 1959, Ser. No. 843,202

3 Claims. (Cl. 2—215)

The present invention relates to a dress-supporting form in the nature of a bustle, and particularly to such a form to be worn by pregnant women to cause their outside clothing to present a more attractive appearance.

When an expectant mother has reached the latter months of her pregnancy and the fetus has grown to a considerable size, and particularly when the fetus has dropped to the lower portion of her abdomen, the expectant mother is caused considerable embarrassment because her body then is at its most unattractive state of her entire pregnancy.

Heretofore, in the latter stages of pregnancy, expectant mothers have worn loose waists or other garments which hang from the breasts and bridge the hollow portion of the woman's body, that is, the space between the breasts and the fullness caused by the fetus she is carrying. Such maternity clothes camouflage to a considerable extent the expectant mother's actual shape.

The present invention contemplates a dress-supporting form which may be secured about the expectant mother's body in the hollow space between the breasts and the fullness caused by the fetus and which will hold the outer garments in line with the upper portion of her body, usually the breasts, and the lower portion of her abdomen. The dress-supporting form in its preferred form comprises a band or strip of relatively stiff material, such as nylon net, which is gathered or pleated on a center string or tape which is secured about the body in the hollow space referred to above. When the string is pulled fairly tightly about the body, the resiliency of the body enables the string to form a crease therein and in the underlying garments, with the body and underlying garments bulging at each side of the crease line. This forces the portions of the band above and below the string outwardly so that they form an effective dress-supporting form to hold the portions of the outer garment opposite the band in substantial alignment with the outer portions of the breasts and the fullness caused by the fetus which the expectant mother is carrying. In this manner the outer garments are caused to present a more slight and attractive appearance and the embarrassment of the expectant mother is lessened.

The invention will be further described in connection with the accompanying drawing which illustrates a preferred form of the dress-supporting form.

In the drawing:

Fig. 1 is an elevational view of the present dress-supporting form;

Fig. 2 is a view taken transversely of Fig. 1 and showing the position which the dress-supporting form assumes when it is secured about a woman's body;

Fig. 3 is a view similar to Fig. 1 showing a supplemental dress-supporting section which may be attached to the center string when the fullness caused by the growth of the fetus increases and it is desired to have the dress-supporting form effective around a greater portion of the expectant mother's body; and

Fig. 4 is a view showing the dress-supporting form se-

2

cured about the body of an expectant mother and how it is effective to hold the portion of the outer garment opposite the hollow portion of her body in alignment with the upper and lower portions of the body.

5 Referring to the drawing, the dress-supporting form comprises a band or strip 1 of flexible, though relatively stiff material. It is shown as nylon net, but any other material having the necessary flexibility and stiffness to make it stand firmly away from the expectant mother's body, such as tulle, crinoline, plastic material, or the like, may be used, if desired. The band 1 is pleated or gathered on a center string or tape 2. While the string or tape 2 may be non-elastic, it is preferred that it be formed of a tape of nylon tricot or other material having some elasticity, since the elasticity of the string makes the dress-supporting form more comfortable to wear.

The band 1 may be of any suitable length and width, but a length of twelve to fifteen inches and a width of three to four inches will be found satisfactory in most instances. If desired, the dress-supporting form may be made with bands of different lengths and widths for use during different stages of the pregnancy, with bands of greater length and greater width being used during the latter stages of the pregnancy.

20 25 If a band having a width of, for example, four inches were used, when the dress-supporting form is secured about the body it will protrude outwardly from the body a distance of two inches both above and below the center string. When the dress-supporting form is to be used, it is passed around the waist section of the expectant mother, and the ends of the center string are tied together. The center string is pulled sufficiently tight that it forms a crease in the undergarments and in the wearer's body. The outward force exerted by the portions of the undergarments and the body above and below the crease line causes the upper and lower portions of the band to protrude outwardly from the body, as shown in Fig. 4, to form a firm support to hold the portion of the outer garment opposite the dress-supporting form away from the body and substantially in line with the outer portions of the breasts and the fullness caused by the fetus having dropped to the lower portion of the expectant mother's abdomen.

30 35 40 45 50 55 60 65 70 As the fetus grows and the fullness becomes greater, it is desirable to have the dress-supporting form band extend around a greater portion of the expectant mother's body. In order that it shall not be necessary to discard the dress-supporting form worn in earlier stages of the pregnancy and to obtain a dress-supporting form having a longer band, a supplemental band is provided which may be secured to the center string in end-to-end position with respect to the band 1. Such a supplemental band is shown in Fig. 3 where the band 1' and center string 2' are the same as the band and center string 2 of Fig. 2, except that the center string does not extend beyond the end of the band 2'. At each end of the band 1', opposite the ends of the center string 2', a loop 3 is provided. When it is desired to increase the effective length of the band 1 of Fig. 1, one end section of the center string 2 is passed through the loops 3 of the supplemental band 1' and the supplemental band positioned on the center string in end-to-end relation to the band 1. This increases the effective length of the dress-supporting form and will cause a greater part of the circumference of the outer garment to be held in line with the upper and lower portions of the body.

If it is desired to still further increase the effective length of the band 1 as the fullness increases, a supplemental band may be strung onto each end section of the center string.

75 80 85 Instead of providing the supplemental band with end loops, like the loops 3, it may be provided with a casing

opposite the center string 2' through which an end section of the center string 2 may be passed to secure a supplemental band thereto.

While the dress-supporting form band has been shown as having the securing string secured to the longitudinal center thereof so that both the upper and lower portions of the band will protrude outwardly to form a firm support for the outer garment, it is to be understood that, if desired, the band could be narrower and the string secured to one edge thereof. However, in most instances the use of a wider band and the attachment of the securing string to the longitudinal center is preferred since it provides two outwardly-protruding sections which will give a firmer support to the outer garment.

From the foregoing it will be apparent that the dress-supporting form of the present invention provides an effective means for holding the portion of the outer garment opposite the hollow space of the expectant mother's body in line with the upper and lower portions of her body without any noticeable weight being placed on her body. Also, the dress-supporting form causes the outer garment to be held so that it presents a more attractive and graceful appearance and thereby makes the expectant mother's body appear more straight up and down. This makes the expectant mother less conscious of her appearance and makes the trying months of her pregnancy more endurable than otherwise would be the case.

Various changes may be made in the details of construction of the dress-supporting form without sacrificing any of the advantages thereof or departing from the scope of the appended claims.

I claim:

1. A dress-supporting form for use by pregnant women

comprising a pleated band of flexible material having sufficient stiffness to hold outer garments away from the wearer's body, and a relatively narrow attaching member secured to the longitudinal midsection of said band and maintaining it in its pleated state, said attaching band having end portions extending beyond the ends of the band to be passed about a wearer's body to secure the band thereto, said band, when secured relatively tightly against a wearer's body, having the portions thereof at each side of said securing member diverging outwardly from said securing member in a generally V-shaped formation.

2. A dress-supporting form as defined in claim 1, in which the band is nylon net.

3. A dress-supporting form as defined in claim 1 in which said pleated band is of a length sufficient to extend across the central portion of a wearer's body, and which includes a second pleated band, similar to said first mentioned band, said second band having loops, the attaching member passing through said loops and maintaining said second band in end-to-end relation with said first band.
